TEXTILE FABRIC OR SIMILAR ARTICLE

William J. Meek, New City, N. Y., assignor to Edgar Fabrics, Inc., New York, N. Y., a corporation of New York

Application September 14, 1950, Serial No. 12,179

Term of patent 7 years

(Cl. D92—1)

To all whom it may concern:

Be it known that I, William J. Meek, a citizen of the United States, residing at New City, in the county of Rockland and State of New York, have invented a new, original, and ornamental Design for Textile Fabric or Similar Article, of which the following is a specification, reference being had to the accompanying drawing, forming part thereof.

In the drawing the single figure of the drawing is a top plan view of textile fabric or similar article, showing my new design.

The design unit is outlined by broken lines and is repeated over the fabric as indicated.

I claim:

The ornamental design for a textile fabric or similar article, as shown and described.

WILLIAM J. MEEK.
